[57] CLAIM

The ornamental design for a plate or similar article,
substantially as shown and described.

DESCRIPTION

FIG. 1 is a bottom plan view of a plate or similar article,
with some of the facets having been omitted for convenience
of illustration, showing my new design;
FIG. 2 is a side elevational view thereof, the reverse
side being a mirror image thereof;
FIG. 3 is a top plan view thereof, the facets as seen
through the side and bottom having been left out for
convenience of illustration; and
FIG. 4 is a sectional view thereof taken along the lines
4—4 of FIG. 3, showing the inner surface, the facets as
seen through the side having been left out for clarity of
illustration.
